LOCOMOTIVE TOY

Earl Harold Wells, Detroit, Mich.

Application July 1, 1946, Serial No. 131,217

Term of patent 3½ years

(Cl. D34—15)

To all whom it may concern:

Be it known that I, Earl Harold Wells, a citizen of the United States, residing at Detroit, in the county of Wayne and State of Michigan, have invented a new, original, and ornamental Design for a Locomotive Toy, of which the following is a specification, reference being had to the accompanying drawing forming part thereof:

Fig. 1 is a side elevational view of the locomotive toy, showing my new design;

Fig. 2 is a top plan view thereof;

And Fig. 3 is a front elevational view thereof.

I claim:

The ornamental design for a locomotive toy, as shown.

EARL HAROLD WELLS.
